CLAIM

The ornamental design for a produce bowl, as shown and described.

DESCRIPTION

FIG. 1 is a perspective view of a produce bowl, showing our new design;

FIG. 2 is a perspective view thereof;

FIG. 3 is a right side view thereof, the left side view being a mirror image thereof;

FIG. 4 is a back view thereof, the front view being a mirror image thereof;

FIG. 5 is a top view thereof; and,

FIG. 6 is a bottom view thereof.

The broken lines in the figures show portions of the produce bowl that form no part of the claimed design.
